7 Claims. (Cl. 226—5)

Machines for packaging cigarettes previously have been proposed, in which the cigarettes through a special shaking device are caused to descend from a magazine into two sets of distributing partitions, from which the cigarettes in a suitable number are then ejected alternately in order to be introduced into boxes or the like. The said sets of partitions, however, were stationary and for the transferring of the cigarettes from the said sets of partitions to a packaging place common to the same, in which they are pushed into the box the machine is provided with a reciprocated slide provided with two compressor chambers which alternately are placed in front of the sets of partitions respectively and a piston common to the same, which pushes the sets of cigarettes from the said chambers and further into the boxes.

This invention relates to a machine for packaging cigarettes, cigars, little cigars and similar rod shaped articles of a considerably simpler construction and operating in a more reliable manner. According to the invention the walls of the partitions are swingably mounted, so that the two sets of partitions may be brought alternately in front of an ejecting device or pistons common to the same, which transfer the cigarettes to the boxes. While a set of partitions is located in front of the said ejecting pistons, cigarettes contained by the second set of partitions are occupying their proper position in the said second set of partitions, which during the subsequent moving of the partitions are placed in front of the ejecting pistons. Owing to the fact that the partition walls are swingably mounted on pins or the like the top ends of the walls impart motion to the cigarettes located in the magazine which facilitates the descending of the cigarettes into the partitions, and besides the partition walls in consequence of a movement relatively to each other which occurs while the partition walls are swung from the one position to the other impart a slight motion of the cigarettes in the partitions, which counteracts any tendency of the cigarettes of clogging in the partitions. For the swinging of the partition walls to the position in front of the ejecting pistons and from the same the said walls are connected to bars, the mechanism being so arranged that the partition walls occupy a substantially parallel position, while the cigarettes descend in the partitions, but converge downwards while in the position for the ejecting of the cigarettes, owing to which fact the cigarettes to be ejected are located closer to each other.

Further, the machine may be so arranged, that to the top ends of the partition walls a rapid reciprocating lateral motion is imparted, through which the falling down of the cigarettes into the partitions is still more accelerated.

For the packaging of cigarettes and little cigars of similar dimensions in two or more superposed rows the machine is provided with means for altering the grouping of the ejecting pistons which is necessary in consequence of the altered oblique position of the sets of partitions while in the ejecting position. Owing to the fact that cigars and little cigars of comparatively great dimensions generally are packaged only in two superposed rows and besides the partitions of the machines effecting the packaging are wider than the partitions of cigarette packaging machines, the pistons, which eject each two cigars, may remain in unaltered grouping at the shifting of the sets of partitions.

Fig. 1 in the accompanying drawings shows in a front view a machine for packaging cigarettes; the partitions are shown in their left operative position. Fig. 2 shows in a similar manner the partitions in their right operative position. Fig. 3 shows in a front view means for altering the grouping of the ejecting pistons or ejectors. Fig. 4 shows a rear pair of shifters and means for adjusting the same. Fig. 5 is a side view of the means for adjusting the shifters. Fig. 6 shows in a front view a machine for packaging cigars or little cigars. Only as much of the machines is shown, as is necessary for the explaining of the invention.

1, Figs. 1 and 2, are walls of sheet metal, which together constitute partitions 2, extending downwards from a magazine for cigarettes. The said partition walls, except the two outermost walls 1¹ of the row, are swingably mounted at their top ends on pins 3 on a carrier 4. The said two outermost walls 1¹ are each pivoted at 5 to a plate 7, which is swingable on a shaft 6 and constitutes the bottom wall of the said cigarette magazine or a part of the same. Shaft 6 is carried by arms 8, which are swingably mounted on pins 9. At their lower parts the partition walls 1, 1¹ are connected by pins to two bars 11, 12 respectively, which are jointed to one another. A link 13 is connected to the bar 12 and to an arm 14, which is swingable on a pin 15 and acted upon by a groove disc 16 provided on a cam shaft 17, which is rotated by the machine. The lower end of the partition walls are bent toward the side, so that they constitute bottom walls of the partitions.

Bars 11 and 12 have oblique positions which are so adapted, that, as the partitions are in their left position, shown in Fig. 1, the walls of the left set of partitions are parallel to each other and the distance between the same is the greatest one along the whole height of the partitions. Consequently, the cigarettes may easily descend from the magazine to the bottom of the partitions. When, however, the 10 walls of the set of partitions now in question have been moved to their right position, shown in Fig. 2, in which position the cigarettes are ejected from the partitions, the walls converge downwards, so that the cigarettes are moved 15 together and constitute rows located closer to each other, which is an advantage regarding the transmitting of the cigarettes into the boxes. The case is quite the same at the right set of partitions, in which the walls are parallel to 20 each other in the position shown in Fig. 2 and converge downwards in the position shown in Fig. 1.

While the partition walls are moved between the stated positions, the top ends of walls act 25 upon the cigarettes located at the bottom of the magazine and effect a certain movement of the same, which facilitates the entrance of the cigarettes into the partitions. Besides, a certain movement of the partition walls relatively to each other takes place during the 30 shifting of the same between the two positions stated above which prevents in an effective manner the cigarettes from clogging in the partitions.

According to the drawings the carrier 4 of the partition walls is fixed to a slide 18, which is movable in a guide and forced by a spring 19 against a cam disc 20, fixed on the shaft 17 and so shaped, that it imparts to the said 35 slide and the top ends of the partition walls a rapid reciprocating shaking motion, which accelerates still more the falling of the cigarettes into the partitions.

Owing to their connection with the outer partition walls 1^x the plates 7, forming parts of the bottom wall of the magazine, are moved 40 rapidly upwards and downwards and are also reciprocated horizontally, which results in the cigarettes moving inwards towards the partition sets and in a sufficient amount of cigarettes being always provided in the space above 45 the said groups. The top edges of the partition walls are located in faces slanting inwards. Owing to this arrangement the top ends of the 50 partition walls and the uppermost cigarettes in the partitions constitute oblique surfaces, on which the cigarettes slide downwards and are distributed substantially uniformly above the partitions.

For the ejecting of the cigarettes from the partitions the machine is provided with pistons 55 21. It is assumed, that in the present case twenty cigarettes are packaged into each box and in three rows. For this reason the pistons 21 are disposed in three rows, as shown in Figs. 1 and 2. As perceived from Fig. 1, the partitions have an oblique position downwards toward the left hand side, while the partitions in Fig. 2 have an oblique position downward 60 toward the right hand side. Owing to this fact, it is necessary to change the groups of pistons 21, so that the pistons are adjusted in accordance with the different slanting positions of the partitions. For this purpose the pistons 21 are 65 provided on three carriers 22, 23 and 24 one for

each horizontal row of pistons. The lowermost carrier 22 is fixed to a slide 25, which is movable in a guide 26, Fig. 4. Slide 25 is reciprocated by an arm 28, which is pivoted at 27 and by means of a roller engages the groove of a disc 29 fixed to the shaft 17. The said arm 28 is fork shaped and embraces a roller 28^x on the slide 25, Fig. 4. The slides 23 and 24 on the other hand are slideable laterally and are held in adjusted positions by a plate spring fixed to the carrier by means of a screw bolt 30. For moving the carriers 23 and 24 together with their pistons into the two different lateral positions shown in Figs. 1 and 2, the machine is provided with two fore arms or shifters 32, 33, which act upon the carriers 23 and 24 respectively, and two rear arms or shifters 34, 35 which act upon the carriers 24 and 23 respectively in opposite directions. As the carrier 23 is shifted toward the right hand side, Fig. 3, the carrier 24 is shifted toward the left hand side, Figs. 3 and 4, and vice versa. The shifter 32 of the front pair is journaled on a shaft 36 and from the hub of the same an arm 37 extends, provided with a toothed sector 38, which meshes with a toothed sector 39 of an arm 40 on the hub of the shifter 33, journaled on a shaft 41. In the same manner the shifter 34 of the rear pair is connected to the shifter 35 by means of arms 42 and 43 provided with toothed sectors 44 and 45 respectively. Shifter 33 is provided with an arm 46, to which a fork shaped link 47 is connected, which embraces a die 48 on the cam shaft and is guided by the same. The said link is forced with its roller 49 against a cam disc 50 on the said shaft by a spring (not shown). The shifter 35 of the rear pair is acted upon in the same manner by a cam disc 51, Fig. 4, a link 52 and an arm 53 connected with the shifter 35. The cam discs 50 and 51 are so adjusted, that, as the shifters 32 and 33 of the fore pair are moved toward the right and the left hand sides respectively the shifters 34 and 35 of the rear pair are moved toward the left and the right hand sides respectively and in this manner the positions of the carriers 23 and 24 shown in Figs. 3 and 4 are gained. At the next shifting of the carriers the shifter 35 moves the carrier 23 toward the left hand side at the same time as the shifter 34 moves the carrier 24 toward the right hand side. The shifting of the carriers is effected, as the slide 25 is in its inner position, shown in Fig. 5. The shifters may be so arranged that they positively hold the carriers in their different operative positions.

As the pistons 21 have ejected the cigarettes in the right set of partitions, Fig. 1, the sets of partitions are transmitted to the position shown in Fig. 2 and the pistons 21 are shifted in the manner stated above whereupon the pistons eject the cigarettes collected in the left set of partitions, while cigarettes are gathered at the bottom of the right set of partitions. In this manner cigarettes are ejected from the sets of partitions alternately and are then further transported into the boxes or covers.

If, as shown in Figs. 1 and 2, the cigarettes are packaged with seven cigarettes in the bottom and top rows and six cigarettes in the middle row, a small piece of sheet metal 62 is fixed to the partition walls 1^x respectively, which prevents the seventh one of the central row from being ejected. The shifting of the pistons of the central row will then be adapted hereto.

The machine for packing cigars and little cigars shown in Fig. 6 is constructed regarding

its principal members in the same manner as the cigarette packaging machine described above. The machine shown in Fig. 6 is adapted to introduce into each cover ten cigars, distributed into two rows each containing five cigars and for that purpose the machine is provided with ten partitions. The ejecting pistons 56 are fixed to a slide 58 common to the same and movable in a guide. The said slide is reciprocated by means of a lever arm 59 and a groove disc on the cam shaft of the machine. Owing to the fact that the partitions of the machine are wide and only two rows of cigars are ejected simultaneously from the partitions, the comparatively thin pistons may be adapted to act upon each two superposed cigars and maintain the positions shown in Fig. 6 also while ejecting cigars from the second set of partitions placed in front of the pistons.

20 The bottom plates 60 of the magazine are connected to the outermost partition walls 54 and suspended in links 61, so that the said plates during the operation of the machine impart to the cigars a motion forwarding the same downwards towards the partitions.

Owing to the fact that the cigarettes etc. may be transferred directly from the partitions to the boxes, the machine may be run with great velocity and consequently with great output.

30 The shown and described packaging machines may, evidently, be modified in some respects without exceeding the limits of the invention.

I claim:

1. In a machine for packaging cigarettes, cigars, little cigars and other rod shaped articles the combination of a magazine containing the cigarettes, two sets of laterally swingable upright walls constituting partitions, in which cigarettes from the magazine are gathered, members adapted to eject cigarettes from the partitions, and means adapted to place the said sets of partitions alternately in front of the said ejecting members.

2. In a machine for packaging cigarettes, cigars, little cigars and other rod shaped articles, the combination of a magazine containing the cigarettes, two sets of laterally swingable upright walls constituting partitions in which cigarettes from the magazine are gathered, members adapted to eject cigarettes from the partitions, means adapted to swing the said sets of partitions and place the lower ends of the same alternately in front of the said ejecting members, and rods connecting the walls and having such a slanting position that the walls of that set of partitions, from which the cigarettes are ejected, converge downwards, while the walls of the second set of partitions are substantially

parallel and occupy the maximum mutual distance along the entire height of the partitions.

3. A machine as claimed in claim 1, characterized by a slide to which the partition walls are pivoted, and means reciprocating the slide transversely to the said walls for shaking the cigarettes downwards into the partitions. 5

4. In a machine for packaging cigarettes, cigars, little cigars and other rod shaped articles, the combination of a magazine for the cigarettes, two sets of laterally swingable upright walls constituting partitions in which the cigarettes from the magazine are gathered, pistons adapted to eject a number of superposed rows of cigarettes from the partitions, the said pistons being arranged in rows in accordance with the rows of cigarettes to be ejected simultaneously, members adapted to swing the said sets of partitions and place the same with their lower ends alternately in front of the said ejecting pistons, 20 and means for changing the positions of the said pistons according to the changed oblique positions of the partition walls, said means comprising laterally shiftable carriers for the rows of pistons, and a device shifting the said carriers. 25

5. A form of execution of the shifting device stated in claim 4, characterized by a number of pairs of associated swingable arms, adapted to the number of laterally shiftable carriers, 30 and means for swinging the said arms, the arms of respective pairs being located on opposite sides of the carriers and acting upon each carrier.

6. In a machine for packaging cigarettes, 35 cigars, little cigars and other rod shaped articles the combination of a magazine for the cigarettes, two sets of laterally swingable upright walls constituting partitions in which cigarettes from the magazine are gathered, members 40 adapted to eject cigarettes from the partitions, means adapted to place the said sets of partitions alternately in front of the said ejecting members, movable plates, which constitute the bottom of the said magazine or parts of the same and have a slanting position inwards, and means connecting the outer partition walls with the said plates, in order that motion may be imparted to the plates, which promotes in the transportation of the cigarettes towards the 45 partitions. 50

7. In a machine as claimed in claim 1 the arrangement that the top ends of the partition walls are located in a surface slanting inwards for facilitating a uniform distribution of the 55 cigarettes above the partitions.

GUSTAF ÖRSTRÖM.
